C. B. JOHNS.

SAND PIPE HEATER.

APPLICATION FILED FEB. 21, 1922.

1,423,429.

Patented July 18, 1922.

INVENTOR.

CHILION B. JOHNS.

BY

Geo. P. Kimmel ATTORNEY.

UNITED STATES PATENT OFFICE.

CHILION B. JOHNS, OF EBENSBURG, PENNSYLVANIA.

SAND-PIPE HEATER.

1,423,429.

Specification of Letters Patent. Patented July 18, 1922.

Application filed February 21, 1922. Serial No. 533,391.

To all whom it may concern:

Be it known that I, CHILION B. JOHNS, a citizen of the United States, residing at Ebensburg, in the county of Cambria and

5 State of Pennsylvania, have invented certain new and useful Improvements in Sand-Pipe Heaters, of which the following is a specification.

This invention relates to the sanding devices employed upon railway locomotive and the like, and has for one of its objects to provide a simply constructed attachment whereby the sand pipe is heated and the accumulation of moisture therein prevented 15 to insure the free flowing of the sand.

Another object of the invention is to provide a device of this character which may be readily attached to and removed from the sand pipe for renewal or repairs, and without 20 detaching the sand pipe.

Another object of the invention is to provide a device of this character in which the heat imparting qualities may be readily increased or decreased without material structural change in the apparatus.

With these and other objects in view the invention consists in certain novel features of construction as hereinafter shown and described and then specifically pointed out 25 in the claims, and in the drawings illustrative of the preferred embodiment of the invention:—

Figure 1 is a side view of a portion of a conventional locomotive, with the improvement applied.

Fig. 2 is an enlarged sectional elevation of the improved attachment.

Fig. 3 is a transverse section on the line 3—3 of Fig. 2.

40 The improved device may be applied to the sand pipes of railway locomotives, trolley cars, or electrically operated motors of various kinds and the like, and it is not desired to limit the invention in this respect.

45 For the purpose of illustration the representation of a portion of a locomotive is shown in which a part of the boiler is indicated at 10, a part of the frame at 11, one of the main drive wheels at 12, a portion of 50 a railway rail at 13, the sand box at 14, and the usual sand pipe at 15, of conventional construction.

At its lower end the sand pipe 15 is externally threaded to receive an internally 55 threaded cap member 16 and a cap member 17 which is not threaded on the pipe

15 and with a section of piping 18 connected to the two cap members. A clamp nut 19 is applied to the threads of the pipe 15 in advance of the nonthreaded cap member 17 60 and operating to firmly clamp the caps 16 and 17 and the pipe section 18 to the sand pipe.

A lock nut 20 is applied to the sand pipe externally of the clamp nut 19 and rounded 65 to form a nozzle to the pipe, and reducing the liability to injury to the pipe in event of its working loose.

A suitable packing, indicated at 21 is disposed between the clamp nut 19 and the cap 70 member 17.

The pipe section 18 is considerably larger than the sand pipe 15 whereby a relatively large space is left between the sand pipe and the pipe section, as shown in Figs. 2 75 and 3.

A support for the sand pipe is formed by a bracket bar 22 attached at 23 to the frame 11 and with a strap 24 encompassing the pipe section 18 and between the confronting edges of the caps 16 and 17 and connected at its ends at 25 to the member 22. The caps thus serve to prevent displacement of the device relative to the members 11 and 22. 80

Surrounding the pipe 15 between the caps 85 16 and 17 are layers of insulation, preferably mica, and indicated at 26, and surrounding the insulation are coils of relatively fine copper wire or the like, and indicated at 27, and between the coils 27 and the pipe 90 section 18 is a wrapping of fire proof material such as asbestos and indicated at 28. The asbestos being a non-conductor of heat prevents the waste of heat from the coils.

A main electric conductor is indicated at 95 29 and coupled to the coils 27 through suitable binder posts, one of which is indicated at 30.

The source of energy for the electric current is not shown as it forms no part of the 100 present invention, but the usual motor carried upon locomotives and trolley cars will be utilized to furnish the required current.

The conductor wires will preferably be carried to the cab of the locomotive through 105 the hand rail, indicated at 31, and provided with a controlling switch indicated at 32, convenient to the engineer.

By this means the electric current will be conveyed to the coils and the heat generated 110 thereby radiated to the interior of the pipe 15 at its discharge or nozzle end, and thus

heat the pipe and prevent the formation of moisture at the base or nozzle end of the pipe and thus effectually preventing the clogging of the pipe.

5 The improved device is simple in construction, can be adapted without material structural change to locomotives and like vehicles of different forms, and operates effectually for the purposes described.

10 The cap nut 16 is threaded onto pipe 15 the thread being slightly tapered at the upper end, so that by screwing cap nut 16 tight, or so far as it will go, a water tight joint is formed between the members 15 and 16 preventing water from entering the heating chamber from above. The cap nut 17 not being threaded is slipped over the end of pipe 15 and the clamp nut 19 with the packing 21 forms a water tight joint below the 15 heating chamber and serves to hold the heater more firmly in place. The combined 20 nozzle and lock nut 20 below the clamp 19 completes the outside construction.

To remove the coil 27 which slips easily 25 into the heating chamber, it is only necessary to unscrew lock nut 20 and clamp nut 19 and remove cap 17; then disconnect the wire at 30 when the coil can be pulled out and a new coil put in.

30 The preferred embodiment of the invention is disclosed in the drawings and set forth in the specification, but it will be

understood that modification within the scope of the claimed invention may be made in the construction without departing from 35 the principle of the invention or sacrificing any of its advantages.

Having thus described the invention, what is claimed as new is:—

1. An attachment for sand pipes comprising 40 cap members attached to the sand pipe at the discharge end in spaced relation, a tubular member connecting said cap members and spaced from the sand pipe, heat imparting means between the tubular member 45 and the pipe, and a combined nozzle device and lock nut attached to the pipe at its discharge end.

2. The combination with a sand pipe externally threaded at the discharge end, a cap 50 device threaded to engage the threaded portion of the sand pipe, a cap member bearing around the sand pipe and unthreaded thereon, a tubular member connecting said cap members and spaced from the sand pipe, 55 a clamp nut engaging the sand pipe and bearing against the adjacent cap member, a combined lock nut and nozzle member engaging the sand pipe externally of the clamp nut, and heat imparting means between the 60 tubular member and the sand pipe.

In testimony whereof, I affix my signature hereto.

CHILION B. JOHNS.
